MARGIN STOP-SETTING MECHANISM FOR
TYPEWRITERSClaude Wellington Brumhill, Leicester, England,
assignor to The Imperial Typewriter Company
Limited, Leicester, EnglandApplication February 15, 1946, Serial No. 647,929
In Great Britain March 8, 1945

1 Claim. (Cl. 197—63)

1 In typewriting and like machines, the travel of the carriage is determined by margin stops which in general require to be adjustable to vary the width of typing or to determine the width of margin. The object of the present invention is an efficient mechanism whereby these stops may be set employing only one hand of the user of the machine.

With this object in view the invention provides in or for a typewriting machine of the kind in which the traverse of the carriage is determined by adjustable margin stops on its co-operating with a centre stop on the frame and in which the carriage is connected to an escapement, a carriage having the combination of a toothed stop rod extending longitudinally in the carriage and having the margin stops mounted on it, a releasable detent on each margin stop for engaging the teeth to lock the stop to the rod, latch mechanism associated with each margin stop which mechanism is capable of being rendered operative prior to such traverse of the carriage as will bring a margin stop to the centre stop and which thereupon engages a frame-mounted member to lock said margin stop temporarily in the central position, and a common manual control on the carriage, including a detent and latch mechanism controlling member extending longitudinally in the carriage, movable in one direction to disconnect the carriage from the escapement to permit free traverse, to release the detents from the stop rod, and to render the latch mechanism operative to permit it to engage the frame-mounted member upon traverse of the carriage and thereby to lock a margin stop temporarily in a central position so that the carriage may be adjusted in relation to said stop, and movable in the reverse direction to connect the escapement to render the latch mechanism inoperative and to connect the detents so that the adjusted margin stop is connected to the stop rod in its adjusted position.

The foregoing and other features of the invention set out in the appended claims are incorporated in the carriage which will now be described as an example with reference to the accompanying drawings in which—

Figure 1 is a side elevation of the carriage;

Figure 2 is a front elevation of relevant portions thereof;

Figure 3 is a section through the carriage;

Figure 4 is a plan of one end of the carriage;

Figure 5 is a longitudinal section through the left hand margin stop shown in Fig. 2 but on a larger scale;

2 Figure 6 is a cross section therethrough looking to the right;

Figure 7 is a cross section looking to the left; and

Figure 8 is a plan thereof.

The carriage is mounted on a slide 10 movable endwise on ball bearings in guides one of which is indicated at 11; it comprises the usual end plates 12 between which the platen 13 is mounted in known manner. This carriage is normally coupled to an escapement (not shown) by means of a toothed rack bar 14 carried by levers 16 at each end that are movable about an axis 15 to raise the rod and thereby to disconnect it from the escapement. Each lever 16 carries a thumb piece 17 by which it may be depressed.

The adjustable margin stops are indicated generally at 18a, 18b; they are of substantially identical construction, are carried by a toothed, horizontal, margin stop rod 19 suitably mounted between the end plates 12 by means 20, and are provided with stop members 21a, 21b, co-operating with a centre stop (not shown) located between them on the body of the machine. Each margin stop incorporates a releasable detent comprising a stirrup 22 transfixed by stop rod 19 and biased upwards by spring 23 so that the lower bar 22' of each leg enters between the teeth; the legs are connected by a cross bar 24 which retains the stirrup.

In order simultaneously to depress the stirrups 22, so as to disengage them from the teeth and to free the stops 18a, 18b, from rod 19, a margin stop release bar 25 extends above them and is carried by levers 26 pivoted on the end frames 12 at 27. The right hand lever 26 is connected by a bridge 28 to a margin stop setting lever 29 (pivoted at 27) having a thumb piece 30 by which it may be depressed to lower release bar 25 so that the latter presses on the tops of the stirrups 22 and frees the margin stops 18a, 18b from the margin stop rod 19. It is an important feature of the invention that this movement also disconnects the escapement by raising the rack bar 14: for this purpose the rack release lever 16 carries a lug 31 which is engaged by the thumb piece 30 of the margin stop setting lever 29 as the latter is depressed. It will be seen from Figs. 2 and 4, however, that the thumb piece 17 projects sufficiently beyond the thumb piece 30 to permit the rack release to be operated independently of the margin stop release.

When the margin stops 18a, 18b have thus

3

been released they are frictionally held, against inadvertent movement by the pressure of release bar 25 (which is to be identified with the detent and latch mechanism controlling member hereinbefore referred to) and by the resilient pressure of the bodies of the stops on the upper surface of rod 19. Simultaneously, latch mechanism is rendered operative, i. e., is placed in condition to operate. This mechanism comprises a latch tongue 32a or 32b on each stirrup which is thereby lowered to operative position in which it is placed to engage, upon such subsequent traverse of the carriage as will bring either margin stop towards the centre stop, in the recess 33 of a spring bolt 34 carried centrally by the guide 11 and provided with spring 34' (Figure 2).

The operation of margin stop setting is therefore as follows. The depression of thumb piece 30 disconnects the carriage from the escapement, releases the stops 18a, 18b from the stop rod 19, and makes ready the latch tongues 32a and 32b. If the carriage be now traversed to the right, the left hand tongue 32b engages the bolt 34 so that the left hand stop 18b is temporarily locked in a central position so that the carriage may then be moved in either direction to bring said stop into the required position along the carriage. The thumb piece 30 is then released, locking the stops 18a, 18b to the stop rod 19 (stop 18b in its adjusted position), releasing the left hand tongue 32b from bolt 34, and locking the carriage to the escapement, margin stop release lever 29 being raised by spring 35 and rack release lever 16 being moved by any suitable spring (not shown). The carriage may then be traversed to the left to bring the left hand stop 18b out of register with the bolt 34, and the operations repeated in respect of the right hand stop 18a. It will be obvious that these operations only require the use of one hand (the right hand) for the carriage to be traversed by that hand, grasping any convenient portion thereof, while the thumb of that hand is employed to manipulate the thumb piece 30.

For convenience in setting the stops, the carriage has a visible scale 36 and indicators 37a, 37b on the stops 18a, 18b which project up behind the paper shelf 38 to co-operate with said scale. On Fig. 1 the double line 39' indicates the wall of a carriage and cover 39, Fig. 4, the side whereof is cut away to disclose the parts which it normally covers.

It has already been mentioned that the two margin stops 18a, 18b are substantially identical. Apart from being right and left hand, their differences reside in the slight offset given to the left tongue 32a on the right hand stop 18a from the stirrup leg 22' (as clearly shown in Fig. 2) whereas the tongue 32b on the other stop 18b is aligned with its stirrup leg (as shown in Figs. 2 and 8), and in the provision of the spacer or distance piece 40 projecting from stop 18b towards stop 18a. A function of this spacer is to prevent the indicators 37a, 37b fouling one another.

The invention is applicable to a detachable carriage i. e., one which is removable from the machine complete with the guides 11.

I claim:

For a typewriting machine of the kind in which the traverse of the carriage is determined by adjustable margin stops on the carriage cooperating with a center stop on the frame and in which the carriage is connected to an escapement, a carriage having the combination of a toothed stop rod extending longitudinally in the carriage and having margin stops mounted thereon, a releasable detent movably mounted on each margin stop for engaging the teeth of the stop rod to lock the stop to the rod, which detent is constituted by a U-shaped member having its legs transfixed by the stop rod and each affording a cross bar to engage among the stop rod teeth, spring means urging said U-shaped member to a tooth-engaging position on the margin stop, latch mechanism associated with each margin stop which mechanism is capable of being rendered operative prior to such traverse of the carriage as will bring a margin stop to the center stop and which thereupon engages a frame-mounted member to lock said margin stop temporarily in the central position, which latch mechanism comprises a latch member on the U-shaped member and movable with the latter, and a common manual control on the carriage, including a detent and latch mechanism controlling member extending longitudinally in the carriage, movable in one direction to disconnect the carriage from the escapement to permit free traverse, and to engage and move the U-shaped members and thereby to release the detents from the stop rod and to render the latch mechanism operative to permit the latter to engage the frame-mounted member upon traverse of the carriage and thereby to lock a margin stop temporarily in a central position so that the carriage may be adjusted in relation to said stop, and movable in the reverse direction to connect the escapement, to render the latch mechanism inoperative and to free the U-shaped members for movement by their spring means into engagement with the teeth of the stop rod whereby the adjusted margin stop is connected to the stop rod in its adjusted position.

CLAUDE WELLINGTON BRUMHILL.
